UNITED STATES PATENT OFFICE.

PETER P. WENDELL, OF HAHN, TEXAS.

METAL CHAIR.

1,250,061.

Specification of Letters Patent. Patented Dec. 11, 1917.

Application filed June 2, 1917. Serial No. 172,443.

To all whom it may concern:

Be it known that I, PETER P. WENDELL, a citizen of the United States, residing at Hahn, in the county of Wharton and State 5 of Texas, have invented new and useful Improvements in Metal Chairs, of which the following is a specification.

This invention relates to improvements in chairs, the object of the invention being to 10 provide a chair which is cheaply constructed of metal, the parts of which may be readily assembled and disassembled and to also provide an improved chair of this character in which the seat may be used either 15 with or without springs.

The invention consists in the construction, combination and arrangement of devices hereinafter described and claimed.

In the accompanying drawings:—

20 Figure 1 is a side elevation of a chair constructed and arranged in accordance with my invention.

Fig. 2 is a vertical sectional view of the same.

25 Fig. 3 is a horizontal sectional view of the same.

The front legs 1 and rear legs 2 are made of angle metal and the rear legs are of sufficient length to extend above the seat 30 and form the back. The front legs are connected together at a point intermediate their ends by a metal cross bar 3 which is secured by means of rivets 4. The rear legs are connected together by metal cross bars 5 which are secured by rivets 6. The lower portions of the front and rear legs 35 are tubular as at 7. The front legs and rear legs are also connected together by bars 8 which are riveted thereto.

40 An angle bar 9 connects the upper ends of the front legs together, a similar angle bar 10 connects the rear legs together at a corresponding height and other angle bars 11 connect the front and rear legs together.

45 The angle bars are secured to the legs by rivets or other suitable fastenings and are arranged with their ends in the angles between the webs of the angle metal legs.

The seat 14 is made of metal and is provided with a down-turned front flange 15 and with side flanges 16. The rear end 50 of the seat extends between the outer webs of the rear legs. The flanges of the seat over-hang the front and side angle bars.

Supporting springs 18 may be also provided for the seat. The upper and lower ends of the supporting springs are connected together by suitable wires. The lower ends of the supporting springs bear on the angle bars which connect the front 60 and rear legs and the upper ends of the springs bear under the seat. The springs are removable and hence the seat may be used on the chair either with or without the springs, as will be understood. A suitable cushion may be used on the seat.

A metal chair thus constructed is extremely cheap and simple, may be readily assembled and disassembled and is strong and durable.

70 While I have herein shown and described a preferred form of my invention, I would have it understood that changes may be made in the form, proportion and construction of the several parts without departing 75 from the spirit of my invention and within the scope of the appended claims.

Having thus described my invention, I claim:—

1. A metal chair having legs comprising 80 angle bars, seat supporting bars secured to the legs, springs on said seat supporting bars, and a metal seat arranged on the upper ends of the springs, the rear corners of the seat being arranged to move vertically 85 in the angles of the rear legs and the seat being extended at its sides and front and provided at the sides and front with downwardly extending flanges over-hanging the corresponding sides of the chair.

2. A metal chair having legs comprising angle bars, seat supporting angle bars detachably secured to the legs and arranged with their ends in the angles between the webs of the angle metal legs, each of said 95 seat supporting bars having an inwardly extending web at its lower side, springs bearing on said webs of the seat supporting bars and a metal seat arranged on the upper ends of the springs, the rear corners of the 100 seat being arranged to move vertically in the angles of the rear legs and the seat being extended at its sides and front and being provided at the sides and front with downwardly extending flanges.

105 In testimony whereof I affix my signature.

PETER P. WENDELL.
